UNITED STATES PATENT OFFICE.

CHARLES SPAETH, OF CLEVELAND, OHIO, ASSIGNOR TO THE MARVEL EQUIPMENT COMPANY, OF CLEVELAND, OHIO, A CORPORATION OF OHIO.

OIL-DISPLAY APPARATUS.

Application filed January 2, 1924. Serial No. 684,034.

My invention relates to an improvement in an oil dispensing apparatus, and as exemplified herein, the improvement comprises means for mounting one or more test tubes upon a pumping apparatus adapted to dispense lubricating oil from tanks, barrels or other containers. Thus, in dispensing oils, particularly lubricating oils, the purchaser is frequently desirous of seeing and testing the oil to determine its grade or quality. A common practice is to exhibit the oil in glass bottles or relatively long test tubes adapted to be conveniently held within the hand and quickly inverted. In this way the color of the oil may be observed and by inverting the tube the viscosity of the oil may also be given a slight test. My main object is to provide a convenient means for mounting one or more of such test tubes upon and in detachable connection with an oil pumping and dispensing apparatus, preferably in a prominent display position within convenient reach of the operator or prospective purchaser so that the tube may be readily removed and inverted and handled by either party.

A further object is to provide a hollow holder, either portable or stationary, into which the test tube or bottle may be inserted to enclose and protect the mouth end of the bottle and to permit the standard bottles in common use to be held in a demountable display position upon the pump or dispensing apparatus with the corked end of the bottle covered and concealed and the cylindrical body of the glass bottle or tube only visible. Then, when the bottle is mounted upon the pump or dispensing apparatus, it will have the appearance of a plain glass cylinder forming a fixed or permanent oil column of the pump or apparatus. In this way the cork of the bottle may also be enclosed and protected and cannot be loosened or removed, either accidentally or purposely, until the bottle is removed from the holder. When a portable metal holder is sleeved upon and secured to the bottle it may also be used to provide a stable support for the bottle when inverted and placed in an upright position upon a table or other flat surface.

In the accompanying drawings, Fig. 1 is a perspective view of an oil pumping and dispensing apparatus equipped with my improvement, showing one of the bottles re-

moved and held in an inverted position within the hand of a person testing the contents of the bottle. Fig. 2 is an enlarged sectional view of the invention secured to the delivery spout of an oil pump or dispensing device, one of the bottles being inclined and partly removed. Fig. 3 is a vertical section on line 3—3 of Fig. 2. Fig. 4 is a perspective view of a glass bottle and its cap or holder inverted. Fig. 5 is a perspective view of the base member of the mounting, and Fig. 6 is a sectional view of a modification of the invention.

It has been a common practice in recent years to dispense lubricating oils directly from shipping drums or barrels or from portable tanks, using a self-measuring pump mounted upon the tank. Dispensing may proceed within a station, shop or automobile garage, or to an automobile on the street at the curb. To enable a prospective purchaser to see and test any given oil dispensed from either a portable or stationary pumping apparatus, I provide a fixed mounting or an attachment A adapted to display a glass bottle or test tube B upon some part of the dispensing apparatus, preferably upon pump C or its discharge pipe or delivery spout D. As shown herein, pump C is mounted upon a barrel or tank E containing the oil, and provided with a delivery spout D extending horizontally above the tank at one side of a vertical pipe F at the top of head G and cylinder H within which the pump operating mechanism is located. The support or mounting A comprises a base member 2 having a round opening 3 horizontally within a bottom portion 4 which is adapted to be sleeved snugly over the straight portion 5 of delivery spout D and secured immovably thereto by a set screw 6. The top 7 of base member 2 is flanged or provided with a pair of shallow round cavities 8—8 adapted to confine and seat a pair of glass bottles or test tubes B—B side by side above the discharge spout or delivery nozzle D, and a pair of upright rods 9—9 are screwed into top 7 intermediate the seating cavities 8—8 to support a flanged cap member 10 apart from and at some distance above base member 2. The bottom face of cap member 10 is formed with shallow round recesses 11—11 directly opposite the seating cavities 8—8 for the bottles B, and each bottle is demountably

held in an upright position between base member 2 and cap member 10 by means of a separate cylindrical holder 12 having a reduced bore or chamber 13 adapted to receive the reduced neck and beaded end 14 of the bottle. The enlarged body part 15 of the bottle is adapted to enter the enlarged mouth or entrance 16 of bore 13 and to be enclosed by the skirting or flange 16' of holder 12 when the holder is sleeved over the neck of the bottle, and the depth of bore 13 and entrance 16 is sufficient to permit holder 12 to be moved longitudinally of the bottle without uncovering the neck, providing this movement is limited by a stop screw 17 carried by the holder and projected inwardly into engaging relation with the annular enlargement or bead 18 on neck 14 of the bottle. A coiled compression spring 19 within bore 13 rests upon the upper end of the bottle or its cork 20 and presses holder 12 upwardly, and the upper end 21 of the holder is reduced in diameter to fit snugly within the round recess 11 in the fixed cap member 10, thereby permitting the bottle and its holder to be detachably secured in a stable upright position within the mounting with the neck end and cork of the bottle completely covered and concealed.

In removing the bottle from the mounting, holder 12 is engaged by the hand and depressed and the bottle tilted on its seat until the holder is entirely disengaged and free from cap member 10. The holder is then retained in the hand and the bottle inverted to observe and test the oil. In restoring the bottle to its place, the bottle is seated within cavity 8, and holder 12 depressed until the bottle is placed upright beneath the cap member whereupon the holder is released to permit the coiled spring to effect interlocking of the holder with the fixed cap member. I have also provided a decorative plate 23 at the top of the cap member 10 upon which the brand of oil or other advertising matter may be displayed, and this plate is fastened by nuts 24 to the tie rods 9-9 and serves to stiffen and brace cap member 10. However, I do not wish to limit myself to the specific form and construction of mounting herein shown and described as the cap and base and tie members may be cast in one piece or united together in any other suitable mechanical way. For example, in Fig. 6, I show a delivery spout or nozzle D' having a socket 25 at its top within which a one-piece mounting A' is removably seated. This mounting comprises a base member and a cap member united together by an integral web or wall 26, and the bottles B-B and their respective holders 12-12 are demountably seated upon the base member at opposite sides of the web or wall 26 in substantially the same way as shown in Fig. 2. A single

bottle or test tube may be demountably supported upon the apparatus, either by the identical means described or by an equivalent arrangement and construction adapted to effect the same objects and results, and the following claims are to be so construed.

What I claim, is:

1. In an oil display apparatus, a closed test tube, in combination with means for removably mounting said closed test tube in an accessible display position upon said apparatus where the tube may be readily removed by hand and inverted for test purposes, said means comprising a locking holder sleeved over one end of said tube. 75
2. In an oil display apparatus, a test tube closed at both ends containing a sample of the oil, a mounting adapted to support said tube removably in display position thereon, and a spring-pressed locking cap 85 for said tube removable together with the tube from said mounting. 89
3. An oil display apparatus, comprising a closed glass test tube, and a mounting and locking means attached in a yielding position upon said tube adapted to permit the tube to be quickly attached and detached from said apparatus. 90
4. An oil display apparatus, comprising a closed glass test tube, a detachable holder 95 for said tube, and a mounting for said tube and holder, said closed tube and its holder being jointly removable from said mounting. 95
5. An oil display apparatus, comprising a mounting, and a closed test tube having a removable holder at one end thereof detachably connected with said mounting and jointly removable therefrom. 100
6. An oil display apparatus, comprising a mounting, in combination with a sealed 105 glass bottle having an enclosing and protecting member at one end thereof, said member having separable interlocking connection with said mounting. 105
7. An oil display apparatus, comprising a 110 mounting, a closed test tube having a cork, a depressible holder enclosing said cork and adapted to support said closed tube in a quickly demountable display position upon said mounting. 115
8. An oil display apparatus, comprising a mounting adapted to seat a closed test bottle of oil removably thereon, and a locking device secured to the bottle and movable relatively to said mounting and bottle 120 adapted to secure the bottle in a quickly removable display position upon said mounting. 120
9. An oil display apparatus, comprising a test bottle of oil having a neck, a mounting 125 adapted to seat said bottle, and a locking holder sleeved upon and enclosing the neck of said bottle and adapted to detachably connect with said mounting, said holder being removable with the bottle. 130

10. An oil display apparatus, comprising a test bottle of oil, a mounting adapted to seat said bottle, and a spring pressed locking member connected with said bottle adapted to interlock with said mounting and to permit convenient detachment and removal of said bottle, said locking member being removable from the mounting together with the bottle.
11. An oil display apparatus, comprising a bottle having a beaded neck, a movable cap member sleeved over said neck containing a spring bearing against said bottle, and a mounting having seats for said bottle and said cap member, said member being removable from its seat together with the bottle.
12. An oil display apparatus comprising a glass bottle having a beaded neck, an enclosure member for said neck, a coiled spring confined within said member, means adapted to secure said member detachably in a movable position upon said neck, and a mounting adapted to seat said bottle and permit
- an interlocking connection with said enclosing member, said bottle and its enclosure member being jointly removable from said mounting.
13. An oil display apparatus, comprising a test bottle, a hollow holder adapted to receive one end of said bottle, and a spring adapted to co-act with said holder in supporting the bottle in free detachable connection with a part of said apparatus, said holder being locked to the bottle and removable therewith from said apparatus.
14. An oil display apparatus, comprising a test bottle having a beaded neck, a hollow holder adapted to receive said beaded neck, a locking element to fasten said holder to said neck and a spring engaging said beaded neck adapted to lock said bottle in a demountable display position upon said apparatus by means of said holder.

In testimony whereof I affix my signature.

CHARLES SPAETH.
